UNITED STATES PATENT OFFICE

159,810

DETACHABLE FRONT FENDER GUARD FOR AN AUTOMOBILE

William G. Hepner, Los Angeles, Calif.

Application July 30, 1948, Serial No. 147,848

Term of patent 7 years

(Cl. D14—6)

To all whom it may concern:

Be it known that I, William G. Hepner, a citizen of the United States, residing in Los Angeles, in the county of Los Angeles, State of California, have invented a new, original, and ornamental Design for Detachable Front Fender Guard for Automobiles, of which the following is a specification, reference being had to the accompanying drawings, forming a part thereof.

Figure 1 is a perspective view of a detachable front fender guard embodying my novel design,

Figure 2 is a side view thereof.

Figure 3 is a vertical sectional view as on a line 3—3 of Figure 2.

The characteristic features of my design reside in the portions shown by means of full lines

in the drawing. The dotted line showing of portions of an automobile in the several drawing figures is for illustrative purposes only.

I claim:

The ornamental design for a detachable front fender guard for an automobile, substantially as shown and described.

WILLIAM G. HEPNER.
